UNITED STATES PATENT OFFICE.

VICTOR VON CZEHWENY, OF DEUTSCHLANDSBERG, AND EDUARD BLÜMEL, OF ST. POLTEN, AUSTRIA.

MATCHMAKING MACHINE.

1,419,999.

Specification of Letters Patent. Patented June 20, 1922.

Application filed January 24, 1919. Serial No. 272,976.

To all whom it may concern:

Be it known that we, VICTOR VON CZEHWENY, managing director, at Deutschlandsberg, in the county of Styria, in the Empire of Austria, and EDUARD BLÜMEL, engineer, at St. Polten, in the county of Lower-Austria, in the Empire of Austria, have invented new and useful Improvements in Matchmaking Machines, (for which we have 5 filed applications in Austria, filed July 27, 1917; Hungary, filed May 25, 1918; Sweden, filed May 24, 1918; Switzerland, filed May 25, 1918; Denmark, filed May 29, 1918; Italy, filed May 31, 1918; Germany, filed 10 May 31, 1918; Holland, filed June 11, 1918; Norway, filed June 18, 1918; Czechoslovakia, filed June 18, 1919; Poland, filed June 23, 15 1920), of which the following is a specification.

20 This invention relates to improvements in match making machines and refers especially to the appliances for pushing the match sticks in the carrier belts of automatic match making machines.

25 In machines heretofore used having means for forcing match sticks into the carrier, the match sticks fall from a supply hopper upon a grooved plate movable toward the carrier, and the match sticks are 30 forced into the carrier by a setting head or the like. With apparatus of that kind it is of great importance that the grooves of the grooved plate prior to their being again filled with match sticks, be cleared of all 35 sticks, splinters, or other particles which might have remained in the grooves from a previous operation, in order to allow the match sticks to assume the proper position in the grooves and to be properly forced 40 into the holes of the carrier. Such clearing of the grooves has been effected in a satisfactory manner by means of needles of suitable length and movable with respect to the grooved plate, but these needles oftened the disadvantage that in consequence of their comparatively great length they 45 were easily bent thus destroying the accuracy of inserting the match sticks.

Constructions in which the setting head is 50 formed integral with the grooved plate presented the drawback that a total clearing

of the grooves along their entire length, as for example by means of a needle comb lowered from above or by similar means, was impossible so that at least the most 55 rearward parts of the grooves always would remain uncleansed. This caused an imperfect falling of the sticks into the grooves of the plate.

Vertical displacement of the setting head 60 with regard to the grooved plate for the purpose of allowing the setting head to be lowered after insertion of the sticks is effected far enough to free the ends of the 65 grooves of the grooved plate has a disadvantage that there is required a complicated mechanism which cannot always be relied upon and which unfavorably effects a reliable horizontal guidance of the 70 grooved plate in a straight line.

Now the appliance of our present invention removes all the said drawbacks in that the setting head at the beginning of the rearward movement of the grooved plate in consequence of a relative horizontal displacement makes free the rear ends of the 75 grooves of the grooved plate thus allowing a comb lowered down into the grooves of the grooved plate during its rearward movement to clean the grooves along their 80 entire length. The said relative horizontal displacement of the setting head may be either a leading movement in the direction of its back stroke or a transverse one, if the setting head is provided also with 85 grooves like the grooved plate. The relative displacement of the setting head in a horizontal direction with regard to the grooved plate allows of a simple and reliable guidance in straight line and in the 90 direction of the insertion of the match sticks so that accuracy in the insertion of the match sticks is ensured.

As regards construction of the appliance the invention may be executed in several 95 modifications as will be hereinafter described with reference to the annexed sheets of drawings.

First it must be observed that the grooved plate may be constructed with grooves alternating in two or more depths in order to be 100 able to insert simultaneously two or more

rows of match-sticks in the carrying belt and all the grooves of different depths may be cleaned simultaneously without the necessity of displacing the grooved plate or the setting head in a vertical direction.

Figures 1 to 4 of the drawing represent in elevation and in four steps of work one modification of the inserting appliance, whilst Figure 5 shows the same in plan.

10 Figures 6 and 7 represent a further modification of the appliance in elevation and in two steps of work;

Figure 8 is a plan of same.

15 Figures 9 to 12 show cross-sections of the grooved plate and of the setting head hereinafter referred to.

In the modification shown in Figures 1 to 5 there is guided on the table 1 of the frame 2 a transverse ledge 3 which supports by 20 means of a bracket 3' the grooved plate 4. In the starting position as represented in Fig. 1 the plate 4 is exactly below the hopper 5 containing the match sticks. At the rear of plate 4 there is arranged on the table 1 25 also the setting head. That part of the setting head which projects over the ledge 3 is in the same plane with the grooved plate 4.

The length of plate 4 in the direction of 30 its movement, that is to say in a direction perpendicular to the carrier 7 which is provided with a series of holes for the reception of the match sticks, is somewhat shorter than that of the match sticks, so that free 35 spaces remain between the ends of the grooved plate 4 and the lower edges of the side walls of hopper 5, through which sticks may drop down which lie transversely in the hopper. In order to allow dropping down of such 40 match sticks also on the rear side of the grooved plate 4 the setting head 6 in the starting position of the parts shown in Fig. 1 is withdrawn far enough so as to allow a free space to remain between its front edge and the rear edge of grooved plate 4 through 45 which free space transversely lying match sticks may drop.

The drive of plate 4 as well as of setting head 6 is effected by means of levers 8 pivoted at 9 to the frame 2. These levers act 50 upon ledge 3 of the grooved plate 4 by means of links 10 and upon setting head 6 by means of links 11. Hence when levers 8 are oscillated about their connection at 9 the grooved plate 4 and the setting head 6 will 55 receive a reciprocating movement on the table 1.

As the setting head 6 is connected to the levers 8 nearer to their ends than the grooved plate 4, the to and fro movement of the grooved plate 4 is a slower one than that of the setting head 6 and the conditions are such that the free space between the setting head 6 and the grooved plate 4 gradually diminishes during the forward movement of 60 the two parts, so that this space disappears

at the end of movement, that is to say, the front end of the setting head 6 abuts the rear end of the grooved plate 4, when the forward movement of the two parts is completed. Figure 3 represents this position of parts, while Figure 2 shows an intermediate position during their forward movement. When the parts are returned the free space gradually increases until at last it attains the dimension as shown in Fig. 1.

75 Figure 4 indicates an intermediate position of parts during the return movement. It is obvious that during the forward movement the setting head follows the grooved plate and approaches it, whereas during the return movement it is leading, and withdraws from it. Actuation of levers 8 is effected by means of eccentrics 13 mounted on a shaft 12 and by eccentric-rods 14.

The operation of the apparatus is as follows:

In the starting position of parts, as shown in Fig. 1, match sticks drop from the hopper 5 upon the grooved plate 4 and each of its grooves receives one of the sticks; the latter 90 slightly project on both sides i. e. in front and in the rear of the grooves. If now levers 8 are moved in a forward direction by the eccentric, the grooved plate 4 and the setting head 6 are moved forward as previously 95 described, the front wall of the hopper 5 retaining all other match sticks which did not fall into the grooves of plate 4. During the forward movement of the grooved plate 4 the setting head 6 closes the hopper 5 at 100 its lower end. During the further forward movement the front edge of setting head 6 finally abuts the rear ends of the match sticks lying on the grooved plate 4 and pushes the same forward in an axial direction until the 105 front end of the setting head abuts the rear edge of the grooved plate 4. In consequence thereof the match sticks project beyond the front edge of the grooved plate 4, far enough to allow the front ends of the match sticks 110 to be inserted in the holes of the carrying belt 7 (Figure 3). This done, the return-movement of the parts takes place again (Figure 4), during which setting head 6 returns quicker than the grooved plate, as 115 before stated, so that soon a free space between its front end and the rear edge of the grooved plate is formed, which gradually increases until it gets as wide as shown in Figure 1.

If desired, also the setting head 6 may be provided with grooves or flutings which align with the grooves of the grooved plate 4 but are slightly shallower than the latter, so that the front end of the setting head still 125 forms an abutment for the match sticks on the grooved plate. In the advanced position of setting head 6, in which the latter closes the lower end of the hopper 5, the match sticks are entering the grooves of the setting 130

head, wherein a preliminary setting in order of those sticks takes place that are to be introduced into the grooved plate, when the latter is again below the hopper 5.

5 During the return-movement of the setting head 6 and of the grooved plate 4 the match sticks being at that time in the grooves of setting head 6 are retained by the rear wall of the match stick hopper 5, so that 10 the same cannot partake in the return-movement of the setting head and are consequently pushed into the grooves of the grooved plate in perfect order.

For cleaning the grooves of the grooved 15 plate during its return-movement there is used a needle comb 15, located between the match stick hopper 5 and the carrier belt 7. This needle comb 15 is supported by a transversal bracket 16 biased downwardly by the 20 action of springs 17 and resting upon supports 18, which in turn rest upon levers 19, pivotally connected to the frame at 20. The free ends of these levers carry rollers 21 which rest upon cam discs 22 on the shaft 25 12. The shape of the cam discs 22 is such that levers 19 and also supports 18 and the bracket 16 with its needle comb 15 are lowered under the action of the springs 17 as soon as a small free space has been formed 30 between the setting head and grooved plate upon their return movement. Into this space the ends of the needles 15 are lowered, the position of the needles corresponding of course to that of the grooves of the grooved 35 plate. While the needle comb is in the lowered position, the return-movement of the grooved plate is progressing (Fig. 4) and the ends of the needles consequently act on the whole length of the grooves and clean 40 the same of all splinters, match sticks and similar obstacles, which might have remained therein. The free ends of levers 19 are then again raised by the cam discs 22 thus raising the needle comb. The latter 45 will remain in its uppermost position, until it again is brought into action after the next following forward movement of the grooved plate.

In the form of the apparatus just 50 described the rear ends of the grooves of the grooved plate have been freed for the entry of the cleaning comb because the setting head in advancing during its return-movement has created a free space between itself and 55 the rear edge of the grooved plate.

In the modification shown in Figs. 6 to 8 of the drawing freeing of the rear ends of the grooves of the grooved plate is obtained as follows:—A portion of the setting 60 head which in this case is formed as a grooved ledge, may be shifted transversely for such a distance, that the grooves of the pusher ledge of same depth as those of the grooved plate are placed in alignment with 65 those of the said plate; by this way the

needle comb may be lowered into the grooves of the grooved ledge and therefore sweeps through the whole length of the grooves during the simultaneous return-movement of the pusher ledge and of the pusher plate. 70 Consequently the two said parts may uniformly execute both their forward and return-movement.

If desired, the pusher ledge may also be provided with shallow grooves, as already 75 described with regard to the foregoing modification. In the normal position of the parts these shallow grooves align with the grooves of the grooved plate, but the front edge of the pusher ledge still forms an abutment for 80 the match sticks lying in the grooves of the grooved plate. The deeper grooves of the pusher plate at least of the same depth as the grooves of the grooved plate are displaced for half a division, so that, if the pusher ledge is transversely shifted for half a division in the one direction or in the other, its deep grooves enter in alignment with the grooves of the grooved plate.

In the modification represented in Figures 90 6 to 8 there is further shown how the principle of construction may be made use of for the simultaneous inserting of two or more rows of sticks by means of only one grooved plate. 95

Upon a table 23 of the frame 24 there is horizontally guided the grooved plate composed of the two parts 25 and 25' connected together. In the transverse slot being left between the two parts 25 and 25' there is 100 placed the pusher ledge 26, movable with the grooved plate 25 in the movements of the latter and still capable of being shifted in transverse direction. The grooved plate needs to be actuated only in a forward and 105 rearward direction and this is effected in a manner similar to that described with regard to the former modification, viz., by means of levers 27, which act upon the grooved plate by means of links 28 and oscillated by means of an eccentric gear on the shaft 29.

In the starting position, shown in Fig. 6, the grooved plate 25 is just below the match stick hopper 30 and receives sticks in its 115 grooves, the rear ends of which abut against the front edge of the pusher ledge 26. The position of the grooved plate 25 relative to the match stick hopper 30 is such, that the front ends of the sticks from the very beginning of action project far enough beyond the grooved plate, to cause them to be inserted in the holes of the carrying belts 31 at the end of the forward movement. 120

For cleaning the grooved plate there is 125 also like in the preceding form a needle comb 32, located between the match stick hopper 30 and the carrying belt 31. Springs 34 tend to press down the transverse bracket 33 of the needle comb; the said bracket being 130

supported by stays 35, which rest upon levers 36 pivoted to the frame 24. The free ends of levers 36 are acted upon by cam rollers 37, thereby producing an up- and down-movement of the needle comb 32.

The stays 35 carry also two slotted guides 38 located above the pusher ledge 26, one being located at each side of the head. Cone guides 39 are carried by the stays 35 below the pusher ledge 26, one of these guides being located at each side of the head. Each end of the pusher ledge 26 is provided with a pin 40, projecting upward and each end of the ledge 26 is also provided with a pin 41 projecting downward. According to the position of the stays 35 either pins 40 engage the slotted guides 38 or pins 41 engage with the guides 39.

The upper guides 38 contain zig-zag slots as may be seen from Figure 8, whereas the slots of the lower guides are straight in the direction of the forward and backward movement of the grooved plate. The upper pins 40 of the pusher ledge 26 are in engagement with the upper guides 38 during the return movement of the grooved plate 25, and therefore the pusher ledge receives a transverse displacement by means of the zig-zag slots or guides 38. The slots or guides 38 are formed and arranged in such a manner, that at the beginning of the return-movement of the grooved plate 25, pusher ledge 26 is slightly transversely shifted in one direction, then it remains in this position for a certain time, and is then shifted back to its former position, so that, when the starting position of the machine is attained, all the parts occupy their normal position.

During the forward movement of the grooved plate 25 the downward projecting pins 41 of the pusher ledge 26 are in engagement with the grooves of the lower guides 39, so that the pusher ledge during its whole forward movement is not transversely shifted. On the contrary, it is forced in a straight line in order to guarantee its efficient action as an abutment on the rear ends of the match sticks on the grooved plate.

Hence after the beginning of the return movement of the grooved plate 25 that is to say after the beginning of the downward motion of levers 36, stays 35 and needle comb 32, the upper slotted guides 38 are brought in engagement with the upward projecting pins 40 of the pusher ledge 26, and the latter is thereby soon slightly shifted in a transverse direction. The needle comb 32 continuing its descending motion is also capable of entering into the deep grooves of the pusher ledge 26 now in line with the grooves of the grooved plate and retains its lowest position during the whole movement of the returning grooved plate.

The grooves of the grooved plate are thereby

swept throughout their entire length. When the needle comb has left the deep grooves of the pusher ledge, the latter is transversely shifted back by the upper slotted guides 38 and as soon as the needle comb has left 70 the grooved plate, the comb is immediately raised by the cam disc 37, whereupon the downward projecting pins 41 of the pusher ledge 26 engage the lower guides 39 thus securing the position of the pusher ledge 75 relative to the grooved plate.

The needle comb is retained in its highest position during the entire forward movement of the grooved plate, and the pusher ledge 26 is guided in a straight line during 80 this whole movement, by the lower guides 39.

Fig. 9 represents in cross-section a grooved plate having grooves alternating in depth for the purpose of allowing the insertion 85 of two rows of match sticks at a time. The pusher ledge in that case may have the cross-section, shown in Fig. 10, from which it can be seen, that the grooves of full depth and of half the depth are displaced for half 90 a division with regard to the cross-section of the grooved plate shown in Figure 9. This is still more apparent in Fig. 11, showing the two cross-sections designed superimposed, the cross-section of the grooved plate 95 being indicated in dashed lines, while that of the pusher plate is in full lines. This figure also shows the relative position of the grooves during the forward movement, that is to say; when the sticks are inserted, and 100 it can clearly be seen how the lower parts of the deep and half deep grooves of the grooved plate are covered by the steps of the pusher ledge, which forms abutment for the match sticks lying in the grooves. On 105 the return movement of the grooved plate the pusher ledge is shifted one step to the right, that is to say, for half of a "division" of the grooved plate. The word "division" indicates the distance between the center 110 lines of two grooves of full depth and of one groove of half depth. In the position of displacement shown in Fig. 12 the steps of full depth of the pusher ledge perfectly agree with the steps of full depth of the 115 grooved plate and the steps of half depth of the pusher ledge likewise agree with the grooves of half depth and the comb provided with short and long needles may be lowered into the pusher ledge and then 120 pass through the whole length of the grooves of the grooved plate.

It is understood that details of the apparatus may be varied without departing from the scope of the present invention as defined in the claims.

What we claim is:—

1. In match making machine, a carrier, a setting-head and match stick support both reciprocable towards and away from the car- 130

rier, and means to cause the setting-head to withdraw horizontally from the support near the beginning of the return movement of the latter.

5. 2. In a match making machine, a carrier, a setting-head and match stick support both reciprocable towards and away from the carrier, and means to reciprocate said setting-head and support so that while both the support and setting-head are approaching the carrier the setting-head will approach the support horizontally and as soon as the setting-head starts its return movement it will withdraw from the support horizontally.

15. 3. In a match making machine the combination of a setting-head, a carrier, a support for holding the match sticks while they are being inserted in the carrier, the setting-head and support being reciprocable toward and away from the carrier, vertically movable cleaning means for cleaning said support, means to cause the setting-head to withdraw from the support horizontally near the beginning of the return movement of the support and means to lower the cleaning means after the setting-head starts to withdraw from the support.

25. 4. In a match making machine, a carrier, a setting-head, a support for holding the

match sticks while they are being inserted in the carrier and means for reciprocating said setting-head and support towards and away from the carrier, said means comprising an oscillating lever, means for connecting the setting-head and support to said lever, the support being connected to the lever nearer to its center of oscillation than the setting-head for the purpose described.

35. 5. In a match making machine, a carrier, a setting-head, a grooved support for holding the match sticks while they are being inserted in the carrier, the setting-head and support being reciprocable toward and away from the carrier, vertically movable cleaning means for cleaning said support and means to shift the setting-head and support relatively to each other near the beginning of the return stroke of the setting-head and support to provide a clearance at the ends of the grooves in the support and means to lower the cleaning means into the clearance thus provided at the end of said grooves.

In testimony whereof we affix our signatures in the presence of two witnesses.

ING. VICTOR von CZERWENY,
EDUARD BLÜMEL.

Witnesses:

Certificate of Correction.

It is hereby certified that in Letters Patent No. 1,419,899, granted June 20, 1922, upon the application of Victor von Czerweny, of Deutschlandsberg, and Eduard Blümel, of St. Polten, Austria, for an improvement in "Matchmaking Machines," errors appear in the printed specification requiring correction as follows: Page 2, line 25, after the word "head" insert the reference numeral 6; page 3, line 67, for the word "grooved" read *pusher*, and line 70, for the word "pusher" read *grooved*; and that the said Letters Patent should be read with these corrections therein that the same may conform to the record of the case in the Patent Office.

Signed and sealed this 21st day of November, A. D., 1922.

[SEAL.]

KARL FENNING,
Acting Commissioner of Patents.
